(57) **CLAIM**

The ornamental design for a ornamental design for a reversible hospital gown, as shown and described.

DESCRIPTION

FIG. 1 is a front view of a reversible hospital gown showing our new design;

FIG. 2 is a front view in an open configuration;

FIG. 3 is a rear view;

FIG. 4 is a rear view in a half-opened configuration; and, FIG. 5 is a rear view in an open configuration.

The dash-dash lines illustrate stitching that forms part of the claimed design.

1 Claim, 5 Drawing Sheets
